SEPARATING SHOES AND LASTS

Original Filed April 2, 1921 4 Sheets-Sheet 4

UNITED STATES PATENT OFFICE

ARTHUR F. PYM, OF SWAMPSOFT, MASSACHUSETTS, ASSIGNOR TO UNITED SHOE MACHINERY CORPORATION, OF PATERSON, NEW JERSEY, A CORPORATION OF NEW JERSEY

SEPARATING SHOES AND LASTS

Application filed April 2, 1921, Serial No. 458,163. Renewed May 7, 1930.

This invention relates to improvements in machines for use in shoe making, and is illustrated herein as embodied in a machine for separating lasts and shoes. The invention **5** may be utilized, also, in some of its aspects, in machines for mounting shoes on lasts. In various of its aspects, however, the invention is not limited to either of these uses.

In the manufacture of boots and shoes the **10** last, over which the shoe has been shaped, must eventually be removed from the shoe. In removing or "pulling" the lasts, it is difficult to avoid such a strain on the shoes as to "break out" or more or less seriously damage **15** some of them.

One object of this invention is to provide improved means for separating lasts and shoes whereby any objectionable strain on the shoes will be reduced to a minimum.

20 In one aspect, the invention comprises a novel machine for removing shoes from lasts in which the last is held on a stationary support while independently movable co-operating members engage the shoe and remove **25** it therefrom. In the illustrated form of this machine, a friction roll is arranged to be rotated in engagement with the counter portion of the shoe, and a second roll is arranged for rotation in engagement with the shoe bottom **30** to move the shoe longitudinally after the counter has cleared the last heel. As the rolls act through friction, they may be arranged to slip before placing such a strain on a tightly-lasted shoe as to break it out.

35 In this aspect, an important feature of the invention resides in a novel actuating mechanism for bringing the co-operating members into engagement with a shoe and removing it from its last. Springs are utilized in **40** order that the engagement may be yielding, and an adjustable abutment positions the bottom-engaging member according to the size of the shoe. Moreover, the mechanism is so arranged that it may be under the **45** constant control of the operator when the styles of shoes to be removed change often, while on the other hand it may be quickly adjusted for automatic actuation when there is a considerable run of shoes of the same **50** style, with the operations varied to suit the

particular style. This flexible control allows variation and adjustment to arrange for the minimum strain which is sufficient to remove a shoe of any given style, and is made possible by an improved stopping and starting mechanism which, while of possible general applicability, is especially adapted to machines of this type. Moreover, whether the machine is operating automatically or under manual control, movement of the shoe-engaging members may be stopped instantly in an emergency. In the illustrated construction, this is done by complete depression of the treadle which controls the stopping and starting mechanism. **55**

In other aspects the invention provides a fabric or belt interposed between the roll and the shoes for keeping the shoes clean when shoes of different colors are being pulled. The hereindisclosed novel method of moving **60** shoes relatively to lasts by placing a fabric in engagement with a shoe, pressing the fabric thereagainst to produce considerable friction, and moving the fabric while thus pressed against the shoe frictionally to move **65** the shoe relatively to the last, is not claimed herein but is disclosed and claimed in United States Letters Patent No. 1,678,165, granted July 24, 1928, upon my copending application, Serial No. 518,294. Moreover, certain **70** novel combinations disclosed but not claimed herein are disclosed and claimed in United States Letters Patent No. 1,678,164, granted July 24, 1928, upon my copending application, Serial No. 443,043. **75**

Various other novel combinations and specific constructions will be obvious from the following description of the accompanying drawings of an illustrative machine, in which **80**

Figs. 1 to 4 are diagrammatic views showing the operation of the machine;

Fig. 5 is a side elevation of the machine with the casing broken away to show the enclosed mechanism; **85**

Fig. 6 is a detail view of the last-pin and its support;

Fig. 7 is an elevation of the opposite side of the machine from Fig. 5, with a cover-plate removed from the casing; **90**

Fig. 8 is a view, partly in section, of the counter-engaging roll;

Fig. 9 is a section taken generally on the line 9—9 in Fig. 7 but with certain cams and levers shown in elevation;

Fig. 10 is a section on the line 10—10, Fig. 7; and

Fig. 11 is a diagram showing the use of a fabric or belt to avoid soiling the shoes.

The machine comprises a last-pin 300, which supports a last L while a roll 100 is brought into engagement with the counter and another roll 200 with the bottom of a shoe S on the last as shown in Fig. 2. The last block B having first been removed, the roll 100 is rotated by suitable gearing until the counter portion of the shoe clears the heel portion of the last, as shown in Fig. 3, whereupon the shoe is moved longitudinally off the last by rotation of the roll 200 in engagement with the shoe bottom.

The actuating mechanism of the machine is inclosed in a casing 20 having a removable cover 22 and providing bearings for shafts 24, 26 and 28. Power is supplied from a motor 30 through a belt 32 to a worm 34 which meshes with a constantly rotating worm gear 36 that is loose on the shaft 24. Secured to the worm gear 36 is a toothed gear 38 engaging a constantly-rotating gear 40 which is loose on the shaft 26 and which in turn rotates a gear 42 that is loose on the shaft 28.

The worm gear 36 is arranged to be secured to the shaft 24 by a Horton clutch 50 (Fig. 9) actuated by elevation of a push-rod 52 against a spring 54, through oscillation of a bell-crank 56 bearing a pawl 58. The bell-crank 56 is oscillated by horizontal motion of a treadle 60 against a spring 62. Actuation of the clutch 50 in this way by the treadle 60 causes one revolution of shaft 24, after which the clutch is disconnected as is usual with this type of clutch, and shaft 24 comes to rest.

Loose on the shaft 26 is a lever 202 carrying a shaft 204, on which is mounted a frame 206 which supports the roll 200. One end of the lever 202 carries a cam roll 208 arranged to be engaged by a cam 210 to rock the lever about the shaft 26 as a fulcrum to pull the roll 200 downwardly away from a shoe which has just been removed from its last, from the position shown in Fig. 4 to that shown in Fig. 1. This action comes just as the shaft 24 stops at the end of its cycle, and the roll 200 remains in its lowered position as shown in Fig. 1 until the next operation of the machine.

When permitted by rotation of the cam 210 out of engagement with the cam roll 208 at the very beginning of the cycle of the shaft 24, the roll 200 is raised into yielding engagement with the shoe by the action of a spring 212 on the outer end of the lever 202.

The tension of the spring 212 may be varied by an adjusting nut 214.

The position of the roll 200 longitudinally of the shoe is determined by a lever 216 that is loose on the shaft 26 and is connected to the frame 206 by a link 218. The opposite end of the lever 216 is held by a spring 220 against an abutment 222 the position of which may be adjusted by a hand wheel and worm 224.

At the proper time in the cycle of operations, the roll 200 is rotated in engagement with the shoe bottom by sprockets 226 and chain 228 driven by the shaft 204 which is rotated by means of a gear 230 meshing with a gear 232 that is fast on the shaft 26. The shaft 26 is rotated from the gear 40, through a clutch indicated generally at 234 (Fig. 9), arranged to be actuated against a spring 236 by a wedge member 238 operated by a rod 240.

The roll 100 is, in starting position, held out of engagement with the shoe by a cam 110 which rocks a bell-crank 102 carrying a cam roll 108. As shown in Fig. 5, the roll 100 is mounted in the upper end of a frame 106, which, at its lower end, is fulcrumed upon the shaft 28 to permit swinging movement of the roll 100 toward and from the counter portion of the shoe S. The bell-crank 102 also is fulcrumed upon the shaft 28. Pivotedly mounted upon an arm of the bell crank 102 is a link 103. A sleeve 105 is rigidly connected to the frame 106, and the link 103 is freely slidable within the sleeve 105. A compression spring 112 surrounding the link 103 normally holds the sleeve 105 down against a stop shoulder 107 formed upon the link 103. When the shaft 24 is rotated in a counterclockwise direction, as viewed in Fig. 5, the rotation of the cam 110 causes the bell crank 102 to be rocked in a counterclockwise direction, and the bell crank 102, through the spring 112, rocks the frame 106 in a counterclockwise direction, carrying the roll 100 yieldingly into engagement with the counter portion of the shoe and causing it to exert a localized pressure against the rear end of the shoe. At the conclusion of the cycle of operations the cam 110 returns the roll 100 to the position illustrated in Fig. 1, against the opposition of the spring 112. A nut 113 is provided for adjusting the pressure of the spring 112.

The roll 100 is rotated for the proper period during the cycle of the machine by sprockets 126 and a chain 128 driven by the shaft 28 which is operatively connected to the gear 42 by a clutch actuated by a push-rod 140 and a wedge member 138 (Fig. 7).

When it is necessary to change frequently from shoes of one color to those of another, the lighter colored shoes may be soiled by coloring matter left on the rolls 100 and 200 by the darker-colored shoes. In such case,

there may be provided fabrics or belts F passing around either or both of the rolls, as shown diagrammatically in Fig. 11. Such belts are also useful to prevent skidding or slipping of the rubber-surfaced rolls when operating on shoes in temper, or when for any other reason a film of water may form on the surface engaging the shoes, as a fabric surface does not slip as readily when wet as does a rubber surface. The belt may be passed around idlers, as shown, or it may be merely in the form of a long strip.

As above described, horizontal oscillation of the treadle 60 trips the Horton clutch 50 and causes one revolution of the shaft 24 to bring the rolls 100 and 200 into engagement with the shoe S, and to move the rolls back to initial position at the end of the cycle. When the machine is to be operated automatically, as in handling a run of shoes of approximately the same style, the clutch-actuating rods 140 and 240, which govern the rotation of the rolls 100 and 200, are operated by a cam 64 on the shaft 24. The cam 64 is engaged by a cam-roll 66 on a three-arm lever 68 pivoted on the frame at 70. One arm of the lever 68 is connected to a sleeve 142, and another to a link 72 operating a lever 74 connected to a sleeve 242.

The sleeves 142 and 242 are connected to clutch-actuating rods 140 and 240 (Figs. 7 and 10) by spring-pressed detents 144, 244 which engage said sleeves and are carried by inner sleeves 146, 246, the latter engaging adjustable abutments 148, 248. Each of these abutments 148, 248 is threaded on a second inner sleeve 250, splined on rods 140, 240, as shown in detail in Fig. 10 for rod 240. Springs 152, 252 are maintained on rods 140, 240 between inner sleeves 250 and adjusting nuts 154, 254, the latter being threaded on the respective rods 140, 240. The detents 144, 244 are arranged to be tripped by adjustable stops 156, 256. When the detents are tripped by these stops, the push-rods 140, 240 are disconnected from the above-described actuating mechanism and are forced to clutch-releasing position by the springs 152, 252 respectively, so that the clutches are opened by the springs inclosed therein, as shown at 236 in Fig. 9. Pins 141, 241 are provided on rods 140, 240 to prevent unnecessary movement of inner sleeves 146, 246 along said rods and to facilitate relatching of the detents.

The further either abutment 148 or 248 is adjusted away from the corresponding sleeve 146 or 246, the greater the throw of the cam 64 required to close the corresponding clutch, and consequently the later in the cycle of operations will roll 100 or roll 200 begin to rotate. The closer the stop 156 or 256 is adjusted to the detent 144 or 244, the less the throw of the cam 64 required to trip the detent, and consequently the earlier in the cycle of operations will rotation of roll 100 or 200

be stopped. The usual adjustment of these parts is such that the roll 100 begins to rotate immediately after engaging the shoe, as shown in Fig. 2, pulling the counter portion of the shoe off the last. The abutment 248 is adjusted to start rotation of the roll 200 when the counter has cleared the last, and the stop 156 is set to stop the rotation of the roll 100 immediately thereafter. The stop 256 may be set to stop rotation of the roll 200, if desired, when the shoe is in the position shown in Fig. 4, or it may be set just too high to be reached by the cam 64, for emergency use as hereinafter described, and the end of the cycle relied upon to stop the roll 200. In any case, at the end of the cycle, the sleeves 142 and 242 are moved, by the rotation of the cam 64, into positions whereat they are re-engaged by the detents 144 and 244 respectively, in readiness for the next cycle.

The exact length of time that the roll 100 should be rotated before rotation of the roll 200 should commence depends on the style of the shoe. When any one style is operated on for only a short period, it is undesirable to be obliged to adjust the abutments 148, 248 and the stops 156, 256 so often, and manual control is preferable. Accordingly, the cam roll 66 is made readily removable, to throw the cam 64 out of operation, and the clutch-actuating rods 140, 240 are arranged for control by vertical oscillation of the treadle 60.

The lever 74 is fixed on a rock-shaft 76, connected by an arm 78 to a link 80, adjustable at 82, and pivoted at 84 on an arm 86 pulled upwardly by spring 88 and arranged to be pushed downwardly by the treadle 60 oscillating a rock-shaft 90. When using this manual control, and after removing the cam-roll 66, the abutments 148, 248 and the stops 156, 256 are so set that a small downward oscillation of the treadle 60 acts through the link 80, the lever 74, the link 72, and the lever 68, to actuate the rod 140 to cause rotation of the roll 100. Slightly greater movement of the treadle 60 acts through the link 80 and the lever 74 to start the rotation of the roll 200, and if desired the stop 156 may be set to stop the roll 100 at the same time. If preferred, the stop 156 may be set to trip the detent 144 and stop the rotation of the roll 100 after the treadle 60 has been pushed a little further down. In either case, the stop 256 is set to trip the detent 244 and stop rotation of the roll 200 when the treadle 60 has been pressed down as far as it will go.

It is to be noted that, whether the machine is being operated automatically or under manual control, complete depression of the treadle 60 stops rotation of both rolls 100 and 200, and is available to prevent damage to the shoe in an emergency. Moreover, as a further emergency measure, either detent 144 or 244 may be tripped by hand. This makes it

possible to operate either roll 100 or 200 separately if desired.

The last pin 300 is carried by a block 302 (Fig. 6) slidable in an arm 304 rising from the casing 20 and adjustable by turning a threaded connection 306. It is pressed by a spring 308 into a position for convenient positioning or removal of the last L. A detent 310, operated by a finger piece 312, holds the last pin in operative position against the tension of the spring 308. The arm 304, the pin 300 and the parts connecting the pin 300 and the arm 304 thus constitute a last support.

15 In operation, if the machine is being operated automatically, the last L carrying the shoe S is placed on the last pin 300 and oscillated downwardly into the position shown in Fig. 1, and the treadle 60 is kicked sideways. 20 Thereupon the rolls 100 and 200 are moved bodily into engagement with the shoe (Fig. 2), the last block B is removed while the shoe is compressed against the last, the roll 100 is rotated to pull the counter portion of the shoe off the heel of the last (Fig. 3), and the roll 25 200 is rotated to push the shoe longitudinally off the last. It is convenient to leave the shoe supported loosely by the last (Fig. 4). The rolls 100 and 200 return to starting position and the actuating mechanism comes to rest. The operator trips the detent 310, whereupon the spring 308 presents the last and the shoe in a convenient position for removal. If anything goes wrong during this 30 35 cycle, the treadle 60 may be completely depressed, to cause the cam roll 66 idly to leave the cam 64 thereby to stop rotation of both rolls 100 and 200.

If the machine is being operated under 40 manual control, the cam-roll 66 having been removed, the procedure is the same except that the operator keeps his foot on the treadle 60 and governs the stopping and starting of the rolls 100 and 200 by depressing the 45 treadle by degrees. The period of rotation of shaft 24 is such that the most tightly lasted shoe can be removed from its last in this way before the cams 110 and 210 return the rolls 100 and 200 to initial position. Emergency use of the treadle 60 is the same as described above.

While I have described an illustrative form of my invention, it is not the intention to limit its scope thereby, or otherwise than by 55 the terms of the appended claims. The term "shoe", as used in the specification and claims, refers either to a finished or partly-finished shoe, as the case may be.

What I claim is:

60 1. In a machine for removing shoes from lasts, in combination, a support to engage a last with a shoe thereon, means acting to move the shoe off the last, and independently movable auxiliary shoe-and-last-separating 65 means arranged to engage the forepart of the

shoe to co-operate with the first named means.

2. In a machine for removing shoes from lasts, in combination, a support to engage a last with a shoe thereon, means acting to move the shoe off the last, auxiliary shoe-moving means, and mechanisms to actuate said means sequentially, said mechanisms being independent of each other.

70 3. In a machine for removing shoes from lasts, in combination, a support to engage a last with a shoe thereon, means for partially removing the shoe from the last, and independently operable means engaging the shoe bottom for completing the removal of the shoe from the last.

75 4. A machine for removing shoes from lasts having, in combination, a support to engage a last with a shoe thereon, means engaging the shoe upper, means engaging the shoe bottom, and mechanism for actuating said means sequentially to cause said means to separate the shoe from the last.

80 5. A machine for removing shoes from lasts having, in combination, a support for a last, and co-operating shoe-engaging members independently and sequentially actuated to separate the shoe from the last.

85 6. A machine for separating shoes and lasts having, in combination, a support to engage a last with a shoe thereon, a member adapted frictionally to engage the shoe bottom and movable in a path heightwise of the shoe to enable it to engage the shoe bottom, and means for moving said member while in engagement with the shoe bottom in a direction tending to separate the shoe from the last.

90 7. In a machine for separating lasts and shoes, a support for a last, and a friction roll movable heightwise of a shoe on the last to engage the shoe, and means for rotating said roll in a direction to effect a movement of separation between the shoe and the last.

95 8. A machine for separating shoes and lasts having, in combination, a last support, a roll to engage a shoe on a last supported thereby, and means co-operating with the roll to separate the shoe and the last.

100 9. A machine for removing shoes from lasts having, in combination, a last support, a member to engage the counter portion of a shoe on a last supported thereby, another member to engage a different portion of the shoe mechanism to move said members into engagement with the shoe, and other mechanism to actuate said members to remove the shoe from the last.

105 10. A machine for removing shoes from lasts having, in combination, a last support, a member to engage the counter portion of a shoe on a last supported thereby, another member to engage a different portion of the shoe, and mechanism to actuate said members in timed relation to remove the shoe from the last.

11. In a machine for separating shoes and lasts, in combination, a last support, a roll engaging the counter portion of a shoe on a last supported thereby, and gearing to rotate the roll thereby separating the shoe and the last. 70
12. A machine for separating shoes and lasts having, in combination, a last support, a roll engaging a shoe on a last supported thereby, a spring to press the roll against the shoe, and means to rotate the roll in a direction to separate the shoe and the last. 75
13. A machine for separating shoes and lasts having, in combination, a last support, a roll engaging a shoe on a last supported thereby, yielding means to press the roll against the shoe, and means to rotate the roll in a direction to separate the shoe and the last. 80
14. In a machine for separating lasts and shoes, in combination, a support for a last, a plurality of friction rolls yieldingly to engage a shoe on the last, and gearing to rotate said rolls in engagement with the shoe. 85
15. In a machine for separating lasts and shoes, in combination, a support for a last, a roll for engaging a shoe on the last to separate the counter portion of the shoe from the last, and a member to move the shoe longitudinally off the last. 90
16. In a machine for separating lasts and shoes, in combination, a support for a last, members to engage a shoe on the last, mechanism to bring said members into yielding engagement with the shoe, and separate mechanisms to actuate said members to remove the shoe from the last. 95
17. A machine for separating lasts and shoes having, in combination, a support for a last, a roll to engage a shoe on the last, means yieldingly to bring the roll into engagement with the shoe, and gearing to rotate the roll in a direction to separate the shoe from the last. 100
18. A machine for separating lasts and shoes having, in combination, a support for a last, a member to engage a shoe on the last, an arm carrying said member, a spring to rock the arm, a cam to rock the arm in opposition to the spring, mechanism to withdraw the cam to permit the spring to bring said member into engagement with the shoe, and means for moving said member in a direction to remove the shoe from the last. 110
19. A machine for separating lasts and shoes having, in combination, a support for a last, a friction roll to engage a shoe on the last, an arm to carry the roll, a spring to move the arm yieldingly to force the roll against the shoe, and gearing to rotate the roll in a direction to separate the shoe from the last by its frictional engagement therewith. 115
20. In a machine for separating lasts and shoes, in combination, a support for a last, a member engaging a shoe on the last, an other member engaging a different portion of the shoe, and mechanism for actuating said members separately and in unison under constant manual control. 120
21. A machine for separating lasts and shoes having, in combination, a support for a last, a member engaging the counter portion of a shoe, a spring pressing said member against the shoe, means for moving said member in a direction to separate the shoe and the last, and means to vary the tension of the spring. 125
22. A machine for separating lasts and shoes having, in combination, a support for a last, a member engaging the shoe, means for moving said member in a direction to separate the shoe and the last, a spring pressing said member against the shoe, and an adjustable stop to determine the position of said member along a line substantially perpendicular to the thrust of said spring. 130
23. In a machine for removing shoes from lasts, in combination, a last support, a plurality of means cooperating to remove a shoe from a last supported thereby, actuating mechanism for said means, and cam mechanism for controlling the application of said actuating mechanism to said plurality of means to actuate said plurality of means in timed relation. 135
24. In a machine for removing shoes from lasts, in combination, a last support, a plurality of means cooperating to separate a shoe and last supported thereby, a clutch to control each means, and mechanism to throw said clutches into and out of operation. 140
25. A machine for separating lasts and shoes having, in combination, a support for a last, a member to engage a shoe on the last, another member to engage a different part of the shoe, and means to actuate said members separately and in unison constructed and arranged to cause said members to separate the shoe and last. 145
26. In a machine for separating lasts and shoes, in combination, a support for a last, a roll to engage a shoe on the last, another roll to engage a different part of the shoe, and means to rotate said rolls separately and in unison. 150
27. In a machine for separating lasts and shoes, in combination, a support for a last, means to separate a shoe from the last, mechanism to actuate said means automatically according to a predetermined cycle, and means for coacting with a portion of said mechanism to perform the cycle under manual control. 155
28. In a machine for separating lasts and shoes, in combination, a support for a last, means to separate a shoe from the last, and mechanism under constant manual control to actuate said means. 160
29. In a machine for separating lasts and shoes, in combination, a support for a last, 165

means to engage a shoe on the last, mechanism relatively to move the support and said means thereby separating the shoe and last, and independently operable manually-controlled separating means to co-operate therewith.

30. A machine for separating lasts and shoes having, in combination, a support for a last, means to engage a shoe on the last, and mechanism under constant manual control relatively to move said means and said support in a direction to separate the last and shoe.

31. A machine for separating lasts and shoes having, in combination, a support for a last, means to engage a shoe on the last, mechanism to cause relative movement of the support and said means in a direction to separate the last and shoe, and a friction roll 20 engaging the shoe to co-operate in separating the last and shoe.

32. In a machine for separating lasts and shoes, in combination, a support for a last, means to engage a shoe on the last, mechanism to cause relative movement of the support and said means in separating the last and shoe, a friction roll engaging the counter portion of the shoe, and gearing to rotate the roll during the separation of the last and shoe.

33. In a shoe machine, in combination, a support for a last, a fabric to engage a shoe on the last, a roll to press the fabric against the shoe, and means to rotate the roll to cause movement of the shoe relatively to the last.

34. In a shoe machine, in combination, a support for a last, a belt to engage a shoe on the last, a roll to press the belt against the shoe, and means to rotate the roll to cause movement of the shoe relatively to the last.

35. A machine for operating on shoes comprising, in combination, a support for a last, means to move a shoe heightwise of a last on the support, means frictionally to move the shoe longitudinally of the last, and cyclic mechanism constructed and arranged to operate said means in predetermined timed relation.

36. A machine for operating on shoes comprising, in combination, a support for a last, means to move a shoe heightwise of a last on the support, means including a roll and gearing to rotate it to move the shoe frictionally longitudinally of the last, and cyclic mechanism to operate said means in predetermined timed relation.

37. A machine for operating on shoes comprising, in combination, a support for a last, means to move a shoe heightwise of a last on the support, means including a roll and gearing to rotate it to move the shoe frictionally longitudinally of the last, and cyclic mechanism including a one-revolution shaft

and cams thereon to operate said means in timed relation.

38. In a shoe machine, in combination, a plurality of means to operate in timed relation on a shoe, and mechanism to actuate said means, said mechanism being constructed and arranged to be adjustable to operate either in a definite automatic cycle or under constant manual control.

39. In a shoe machine, in combination, means to operate on a shoe, a plurality of clutches controlling said means, and clutch-controlled mechanism to throw said clutches into and out of operation in timed relation.

40. In a shoe machine, in combination, a support for a last, means engaging a shoe on the last, mechanism including a clutch to perform a cycle of movements relatively moving the shoe and the last, and a cam to throw said clutch into and out of operation during the cycle.

41. In a shoe machine, in combination, a support for a last, means including a clutch to operate on a shoe on the last according to a definite cycle, mechanism connected with said clutch automatically to throw said clutch into and out of operation during the cycle, and means for disconnecting said mechanism from the clutch.

42. In a machine for use in making shoes, in combination, a support for a last, and mechanism to perform a cycle of movements relatively moving the shoe and the last, said mechanism comprising a clutch, a cam, connections operated by the cam to actuate the clutch, and means to adjust the connections to cause the actuation of the clutch by the cam to take place at various positions of the cam.

43. In a machine for use in making shoes, in combination, a support for a last and mechanism to perform a cycle of movements relatively moving the shoe and the last, said mechanism comprising a clutch, a lost-motion device to close the clutch, means to vary the extent of the lost motion required to close the clutch, adjustable means to disconnect said device, and a spring to open the clutch when said device is disconnected.

44. In a machine for use in making shoes, in combination, a support for a last, and mechanism to perform a cycle of movements relatively moving the shoe and the last, said mechanism comprising a clutch, an arm to actuate said clutch, a connection through which said arm acts, and a cam to operate the arm, said connection being adjustable to vary the time in the cycle of movements of the cam at which the clutch is actuated by causing actuation of the clutch to be effected by a greater or less throw of the cam.

45. In a machine for use in making shoes, in combination, a support for a last, and mechanism to perform a cycle of movements relatively moving the shoe and the last, said mechanism comprising a clutch, an arm to

5 actuate said clutch, a connection through which said arm acts, a cam to operate the arm, said connection being adjustable to vary the time in the cycle of movements of the cam at which the clutch is actuated by causing actuation of the clutch to be effected by a greater or less throw of the cam, and means to disconnect the clutch from the arm, said means being adjustable to vary the length of time 10 the clutch is closed.

15 46. In a machine for use in making shoes, in combination, a support for a last, and mechanism to perform a cycle of movements relatively moving the shoe and the last, said mechanism comprising a clutch, a treadle to throw the clutch in when it is depressed, and means to throw the clutch out when the 20 treadle is further depressed.

25 47. In a machine for use in making shoes, in combination, a support for a last, and mechanism to perform a cycle of movements relatively moving the shoe and the last, said mechanism comprising a plurality of stopping and starting mechanisms, a member to actuate said mechanisms, a connection including an adjustable device and a detent between each mechanism and the member, and an adjustable abutment to engage each 30 detent, said devices and said abutments being arranged so that each mechanism may be started by movement of said member in any desired degree and stopped by an abutment tripping a detent by any desired further movement of said member.

35 48. In a machine for use in making shoes, in combination, a support for a last, and mechanism to perform a cycle of movements relatively moving the shoe and the last, said mechanism comprising a clutch-actuating 40 rod, a rod-actuating sleeve thereon, a second sleeve yieldingly connected to the rod, and an abutment adjustably threaded on the second sleeve and arranged to be engaged by the first sleeve to move the clutch-actuating 45 rod.

50 49. In a machine for use in making shoes, in combination, a support for a last, and mechanism to perform a cycle of movements relatively moving the shoe and the last, said mechanism comprising a clutch, a member to actuate the clutch, an arm to move said member, and a detent connecting the arm and said member.

55 50. In a machine for use in making shoes, in combination, a support for a last, and mechanism to perform a cycle of movements relatively moving the shoe and the last, said mechanism comprising a clutch, a member to actuate the clutch, an arm to move said member, a detent connecting the arm and said member, and an abutment to trip the detent to disconnect the arm and said member.

60 51. In a machine for use in making shoes, in combination, a support for a last, and mechanism to perform a cycle of movements

relatively moving the shoe and the last, said mechanism comprising a clutch, a member to close the clutch, a cam, a lost-motion connection operated by the cam to move said member, and means to vary the amount of motion 70 lost before the clutch is closed.

52. A machine for separating lasts and shoes having, in combination, a support for a last, means to engage a shoe on the last, mechanism relatively to move said support 75 and said means in a direction to separate the last and shoe, and manually controlled means to stop said relative movement in an emergency.

53. A machine for separating lasts and 80 shoes having, in combination, a member engaging a last, another member engaging a shoe on the last, mechanism to move one of said members relatively to the other in a direction to separate the shoe and last, and 85 means to disconnect said mechanism and said member in an emergency.

54. In a machine for separating lasts and shoes, in combination, a member engaging a last, another member engaging a shoe on the 90 last, mechanism to move one of said members relatively to the other in separating the shoe and last, and a connection between said mechanism and said member, the connection including a detent which may be tripped to 95 disconnect said member from the mechanism in an emergency.

55. In a machine for separating lasts and shoes, in combination, means to separate a last and shoe, and a manually-controlled member to throw said means out of operation in an emergency.

56. In a shoe machine, in combination, a plurality of shoe-engaging rolls, mechanism to actuate said rolls in timed relation, and 105 means to vary said relation.

57. In a shoe machine, in combination, a plurality of shoe-engaging rolls, gearing to rotate one of said rolls, means to stop the rotation of said roll, separate gearing to rotate another roll, means to start said second roll in timed relation to the stopping of said first roll, means to vary the time of stopping the first roll, and means to vary the time of starting the second roll to maintain said 115 timed relation.

58. In a shoe machine, in combination, a plurality of shoe engaging rolls, mechanism to rotate one of said rolls for a variable length of time, mechanism to start rotation of another roll in timed relation to the termination of the period of rotation of the first roll, and means to vary said timed relation.

59. A shoe machine comprising, a combination, a shoe-engaging roll, means to rotate the 125 roll, mechanism operating in a cycle, means controlled by said mechanism for stopping and starting the rotation of the roll at predetermined points in the cycle, and connections releasable during the operation of said 130

cycle and disposed between said mechanism and the stopping and starting means.

60. A shoe machine as defined in claim 59, having also means to vary the points in the cycle at which the stopping and starting of the rotation occurs.

61. A shoe machine comprising, in combination, a shoe-engaging roll, gearing to rotate the roll, a clutch governing the operation of the gearing, a cam to actuate the clutch, and releasable connections between the cam and the clutch.

62. A shoe machine as defined by claim 61, having also means to vary the position of the cam which will actuate the clutch.

63. A shoe machine comprising, in combination, a shoe-engaging instrumentality, a one-revolution shaft, connections to operate said instrumentality at a predetermined and adjustable angular position of said shaft, and connections to throw said instrumentality out of operation at a different predetermined and independently adjustable angular position of the shaft.

64. A shoe machine comprising, in combination, means for operating on a shoe, mechanism going through a definite cycle and stopping and starting the operation of said means at predetermined points in the cycle, and abutments adjustable to determine the points in the cycle at which the stopping and starting will occur without affecting the movement of said mechanism through said definite cycle.

65. A shoe machine comprising, in combination, a roll, gearing to rotate the roll, a clutch to stop and start the operation of the gearing, an arm to operate the clutch, means to vary the throw of the arm necessary to operate the clutch to start the roll, and separate means to vary the throw of the arm necessary to operate the clutch to stop the roll.

66. A shoe machine comprising, in combination, a roll, gearing to rotate the roll, a clutch to stop and start the operation of the gearing, an arm to operate the clutch, means to vary the throw of the arm necessary to operate the clutch, and an adjustable abutment to disconnect said arm to throw the clutch out of operation.

67. In a machine for separating shoes and lasts, in combination, a last support, a roll engaging the counter portion of a shoe on a last supported by said last support, and means for rotating the roll thereby separating the shoe and the last.

68. In a machine for separating shoes and lasts, in combination, a last support, a roll, means for effecting relative movement between said last support and said roll to bring into engagement said roll and the counter portion of a shoe on a last supported by said last support, and means for rotating said roll to separate the shoe from the last.

69. In a machine for separating shoes and

lasts, in combination, a last support, a roll mounted for movement toward and from the counter portion of a shoe on a last supported by said last support, means for moving said roll into engagement with the counter portion of the shoe, and means for rotating said roll to separate the shoe from the last.

70. A machine for separating shoes and lasts having, in combination, a support for a last with a shoe thereon, means adapted to engage the outside of the shoe, said means acting to move the shoe off the last, and independently movable auxiliary shoe-and-last-separating means arranged to engage the outside of the shoe to cooperate with the first named means.

71. A machine for removing shoes from lasts having, in combination, a support for a last with a shoe thereon, cooperating members adapted to engage the outside of the shoe, and means for actuating said cooperating members sequentially to separate the shoe and the last.

72. A machine for separating shoes and lasts having, in combination, a support to engage a last with a shoe thereon, a roll mounted for both bodily and rotary movement, said roll being adapted frictionally to engage the shoe, means for moving said roll bodily into engagement with the shoe, and means for rotating said roll in a direction to separate the shoe and the last.

73. A machine for separating shoes and lasts having, in combination, a support for a last with a shoe thereon, a roll mounted for movement lengthwise of the shoe, means for moving said roll to bring it into engagement with the counter portion of the shoe, and means for rotating the roll in a direction to separate the shoe and the last.

74. A machine for separating shoes and lasts having, in combination, a support for a last with a shoe thereon, a member adapted frictionally to engage the counter portion of the shoe, a carrier for said member mounted for movement to bring said member into and out of engagement with the counter portion of the shoe, said member being mounted in said carrier to permit rotary movement of said member with respect to said carrier, and means independent of said carrier for effecting rotary movement of said member in a direction to move the shoe heightwise of the last.

75. In a machine for separating shoes and lasts, in combination, a support for a last with a shoe thereon, a movable member adapted to engage the shoe, means for moving said member into engagement with the shoe, and independently controlled means for moving said member in a direction to separate the shoe and the last.

76. In a machine for separating shoes and lasts, a support for a last with a shoe thereon, means for exerting a localized pressure

against the rear end of the shoe, and means for effecting relative movement heightwise of the shoe between said support and said pressure exerting means to cause separation 5 between the heel portion of the shoe and the last.

77. A machine for operating on shoes comprising a support for a last, a roll, and means for rotating said roll against the counter portion of a shoe on a last carried by said support to effect relative movement between the shoe and the last.

78. A machine for operating on shoes comprising a support for a last, a roll, means for 15 causing relative movement between said last support and said roll to effect engagement between the counter portion of a shoe on a last carried by said support and said roll, and means for rotating said roll to effect relative movement between the shoe and the last.

79. A machine for operating on shoes comprising a support for a last, a roll, means for moving said roll into engagement with the counter portion of a shoe on a last carried by 25 said support, and means for rotating said roll to effect relative movement between the shoe and the last.

80. In a machine for effecting relative movement between lasts and shoes, a last support, a roll engageable with the counter portion of a shoe on a last supported by said last support, a roll engageable with the bottom of the shoe, means for rotating the first-mentioned roll in a direction to effect relative heightwise movement between the counter portion of the shoe and the heel of the last, and means for rotating the second-mentioned roll in a direction to move the shoe longitudinally with respect to the last.

81. A machine having, in combination, means for effecting relative movement between a shoe and its last, automatic mechanism for controlling said means, and operator-actuated mechanism for controlling said 45 means independently of said automatic mechanism.

82. A machine having, in combination, a plurality of shoe-engaging members for effecting relative movement between a shoe and its last, driving connections for each of said members, means for independently disconnecting each of said connections, and a common control means for said disconnecting means.

83. A machine having, in combination, a plurality of shoe-engaging members for effecting relative movement between a shoe and its last, a driving connection for each of said members, means for independently disconnecting each of said connections, and means for automatically actuating said disconnecting means in timed relation.

84. A machine having, in combination, a plurality of shoe-engaging members, driving 65 means for said members, and mechanism for

causing said driving means to operate said members in a cycle for effecting relative movement between a shoe and its last, said mechanism including means for independently disconnecting each of said members from said driving means.

In testimony whereof I have signed my name to this specification.

ARTHUR F. PYM.
